Clara L. Motta

BY Henry J. Webster
ATTORNEY

UNITED STATES PATENT OFFICE.

CLARA L. MOTTA, OF MODESTO, CALIFORNIA.

DESIGN FOR A BRASSIÈRE.

60,156.

Specification for Design.

Patented Jan. 3, 1922.

Application filed April 18, 1921. Serial No. 462,448. Term of patent 14 years.

To all whom it may concern:

Be it known that I, CLARA L. MOTTA, a citizen of the United States, residing at Modesto, in the county of Stanislaus and State of California, have invented a new, original, and ornamental Design for a Brassière, of which the following is a specification, reference being had to the accompanying drawing, forming part thereof, and in which—

Fig. 1 is a front view of the brassière, and

Fig. 2 is a rear view thereof, both views being in perspective.

I claim:

The ornamental design for a brassière as shown.

CLARA L. MOTTA.
